UNITED STATES PATENT OFFICE

FREDERICK CHARLES WINBY, OF WESTMINSTER, ENGLAND.

RAILWAY-RAIL AND FISH-JOINT, &c., FOR RAILWAY-RAILS.

SPECIFICATION forming part of Letters Patent No. 284,155, dated August 28, 1883.

Application filed February 17, 1883. (No model.) Patented in England June 7, 1882, No. 2,678.

To all whom it may concern:

Be it known that I, FREDERICK CHARLES WINBY, a subject of the Queen of Great Britain, residing at Palace Chambers, St. Stephens, 5 in the city of Westminster, England, have invented certain new and useful Improvements in Railway-Rails and in Fish-Joints and Fish-Joint Chairs for Railway-Rails, (for which I have received Letters Patent in Great Britain, 10 No. 2,678, dated June 7, 1882,) of which the following is a specification.

In order to give additional bearing-surface between fish-plates or the jaws of fish-joint chairs and the rails of railways I reduce the 15 thickness of the vertical web of the rail at the rail ends where the fish-plates are to be secured to it. This allows of the fish-plates being made thicker along their top and bottom edges where they abut against the head 20 and foot of the rails, and in this way a greater extent of bearing-surface is obtained between the top and bottom of the fish-plates and the head and foot of the rails, respectively. It is not necessary that the whole depth of the web 25 of the rail should thus be reduced in thickness; but by the best plan the web has made in it, on each side at the ends of the rail, a groove where it meets the head, and another groove where it meets the foot, the central 30 part of the web at the ends of the rail being left unaltered. The inner sides of the fish-plates or jaws are made with projections corresponding with the grooves in the rail ends, these 35 projections being made at the top and the bottom edges of the fish-plates, the intermediate portions of the inner faces of said plates being grooved or depressed correspondingly with the amount of their projections. The fish-plates may be rolled with the projections 40 on them. The grooves on the opposite sides of the rail-web at the rail ends may be produced by means of circular cutters or saws, or they may be molded upon the sides of the web by a press, or may be produced at the 45 time when the rail is being rolled. The fish-plates may be formed either with or without prolongations extending below the foot of the rails, as desired. In some cases I connect together the two fish-plates which are on the 50 opposite sides of the rails by a connection below the rails, and I make this connection to

extend outward along each side so as to form a joint-chair which may be made to rest on a sleeper or directly upon the ballast, if preferred.

Figures 1 show a cross-section and side elevation of the ends of two rails coupled together by fish-plates formed as above described. Figs. 2 show similar views of a fish-joint in which the fish-plates are made to lap 60 under the foot of the rails. Figs. 3 show similar views of a fish-joint in which the fish-plates are not only made to lap under the foot of the rails, but are also prolonged for a distance downward. Figs. 4 show similar views 65 of a fish-joint in which the fish-plates are at the bottom held by a wedge-piece into a joint-chair. Figs. 5, 6, 7, and 8 show similar views 70 of other fish-joints, in which the fish-plates are held into chairs of different forms and constructions, the nature of which is clearly shown by the several figures.

In each of the examples shown the inner face of that part of the fish-plates which is to abut against the vertical web of the rail is 75 made with a longitudinal groove in it along its center, so producing two longitudinal projections along the inner face of this part of the fish-plate, one along the top, the other along the bottom. On both sides of the rails at 80 their ends longitudinal grooves corresponding to these longitudinal projections are formed, as above described, in the vertical web. The fish-plates are as usual secured by bolts and nuts to the sides of the rails.

In each of the figures the rails are shown to be of the same section, but they might be of other sections. By forming the longitudinal grooves in the sides of the web at the end of the rails in the manner above described, just 90 above and below the foot and head of the rails, respectively, the radius curve between the head or foot and web can be diminished where the grooves are formed. This gives still more extended bearing-surface than if the same 95 curvature were maintained.

In Fig. 4 the fish-plates are at the bottom locked together and prevented from bending outward away from one another by a chair, A, into which they are locked by a wedge-piece, 100 B, drawn downward by keys C driven through slots in bolts D. In Fig. 5 they are held to-

gether in a somewhat similar chair by wedge-keys B. In both these arrangements the chairs are designed only to lock together the lower parts of the two fish-plates on the two sides 5 of the rails, and not to take any bearing upon the ballast.

In Fig. 6 the chair A is shown to be of a form to rest on and be affixed in the ordinary manner to a wooden sleeper. The fish-plates 10 are also wedged and held in the chair by a wooden key, B. In Figs. 7 and 8 the chairs A are shown to be of a form to rest upon the ballast and so give support to the joint. In 15 all cases the chairs have the fish-plates tightly secured in them by means of wedges or wedging devices, it should be noticed.

Having thus described the nature of my invention, and the manner of performing the same, I would have it understood that I claim—
20 1. A railway-rail constructed, as described, with the grooves at its ends in its web, respectively just below the head and just above the foot of the rail, to receive the projections at

the tops and bottoms of the inner faces of the fish-plates, substantially as set forth.

2. The combination of the rails having the grooves at their ends in their webs, respectively just below the heads and just above the feet of the rails, and the fish-plates provided with the projections on their inner faces at 30 their tops and bottoms to enter the grooves of the rails, as and for the purpose set forth.

3. The combination of the rails, the fish-plates provided with projections on their inner faces engaging with grooves at the ends 35 of the rails in their webs, respectively just below the heads and just above the feet of the rails, the chair, and the means by which the fish-plates are wedged in the chair, as and for the purpose described.

FREDERICK CHARLES WINBY.
